(57) **CLAIM**

The ornamental design for a clear clasp reusable envelope, as shown and described.

DESCRIPTION

FIG. 1 is a top plan view of a clear clasp reusable envelope in accordance with the new design, showing the envelope in an opened position;

FIG. 2 is a top plan view thereof, showing the envelope in a closed position; and,

FIG. 3 is a top perspective view thereof, showing the envelope in a partially opened position.

The broken line showing in FIGS. 1-3 is included for the purpose of illustrating portions of the clear clasp reusable envelope and forms no part of the claimed design.
